UNITED STATES PATENT OFFICE.

LEE W. BARBER AND EDWIN W. WEBB, OF CHICAGO, ILLINOIS,
ASSIGNORS TO AMERICAN STEEL FOUNDRIES, OF NEWARK,
NEW JERSEY, A CORPORATION OF NEW JERSEY.

TRUCK-BOLSTER.

No. 828,870.

Specification of Letters Patent.

Patented Aug. 21, 1906.

Application filed December 19, 1905. Serial No. 292,431.

To all whom it may concern:

Be it known that we, LEE W. BARBER and EDWIN W. WEBB, citizens of the United States, residing at Chicago, in the county of Cook and State of Illinois, have invented certain new and useful Improvements in Truck-Bolsters; and we do hereby declare the following to be a full, clear, and exact description of the invention, such as will enable others skilled in the art to which it appertains to make and use the same.

Our invention relates to metallic truck-bolsters, and has for its object to improve the same in the several particulars herein-after mentioned.

The invention consists of the novel devices and combinations of devices hereinafter described, and defined in the claims.

The invention is illustrated in the accompanying drawings, wherein like characters indicate like parts throughout the several views.

Referring to the drawings, Figure 1 is a plan view of the improved bolster. Fig. 2 is a view principally in side elevation, but partly in vertical section, on the line $x^2 x^2$ of Fig. 1. Fig. 3 is a detail in bottom plan view, showing one end of the truck-bolster with some parts removed, with some broken away, and with some sectioned. Fig. 4 is a vertical section taken on the line $x^4 x^4$ of Fig. 3, but with the tension member and lock-block removed. Fig. 5 is an end elevation of the bolster-body shown in Fig. 4. Fig. 6 is a bottom plan view of the lock-block removed from working position. Fig. 7 is a plan view with some parts broken away, showing one end of a truck-bolster of slightly-modified construction; and Fig. 8 is a section taken on the line $x^8 x^8$ of Fig. 7.

The preferred construction illustrated in Figs. 1 to 6, inclusive, will first be described. The body or compression member of the bolster illustrated in the views noted is in the form of a cast-steel channel-bar 1, and the tension member is in the form of a flat steel bar 2. A strut or center post 3 of suitable construction is interposed between the central portions of the said members 1 and 2, and the said member 1 is provided with a suitable center-bearing 4. Lock-blocks 5 are arranged to interlock with the end portions of the compression member 1 and are

themselves arranged to be held in working positions by the end portions of the tension member 2. The compression member 1 is formed with box-like ends having inclined upper internal bearing-surfaces 6, lower bearing-flanges 7 and 8, and end notches 9, which latter are formed in the vertical side webs of the said member 1.

The ends of the tension member 2 are passed through the box-like ends of the member 1 and are pressed against the inclined bearing-surfaces 6 thereof by the lock-blocks 5. These lock-blocks 5, it will be noted, are wedge-shaped and are of such size that they fit snugly within the box-like ends of said member 1 and rest upon the bearing-flanges 7 and 8. The lock-blocks 5 at their outer ends and side portions are formed with projecting lock-lugs 10, that fit in the notches 9 in the ends of the member 1 and are provided with forwardly-extended portions 10^a, that overlap the side webs of the compression member 1 adjacent to said notches 9 and prevent spreading of the said flange.

At the sides of their inner portion the blocks 5 are formed with stop-flanges 5^a, that are adapted to engage with stop-flanges 7^a of the compression member 1 to thereby positively limit the rearward movements of said blocks. After the lock-blocks 5 have been placed in working positions the ends of the tension member 2 are bent down over and against the outer end webs of the said blocks and are secured thereto preferably by rivets 11. It will thus be seen that when the ends of the tension member 2 are turned down, as shown in Fig. 2, irrespective of the rivets, they hold the lock-blocks 5 in working position. Also independently of the rivets the lock-blocks 5 lock the ends of the tension member 2 to the ends of the compression member 1. Under downward strains on the central portion of the bolster the wedge-shaped lock-blocks 5 are by the downturned ends of the tension member 2 pressed inward, and when pressed inward they press the ends of the tension member with increased force against the inclined bearing-surfaces 6 of the compression member 1. For additional strength and safety it is, however, desirable and probably necessary to rivet the ends of the tension member

2 to the lock-blocks 5. However, the wedge action of the lock-blocks and the down-turned ends of the tension member greatly reduce the shearing action upon the rivets, 5 and consequently the number of rivets or similar devices which it is necessary to employ.

A bolster constructed as above described, while very strong and durable, is cheap to 10 construct and may be very quickly put together.

In the modified construction illustrated in Figs. 7 and 8 the compression member 1 is in the form of a rolled channel-bar, and the 15 lock-block 5 is riveted to the flanges of said member 1 and has at its outer portion laterally-projecting L-shaped lock-lugs 10^b, that overlap the end portions of the depending flanges of said channel-bar 1 and also overlie 20 a portion. The horizontal web of the compression member 1 is slit at its ends and turned upward at 1^a. A spacing-block 12 is interposed between the tension member 2 and the overlying web of the member 1 and 25 is riveted to the latter. Rivets 13 and 14 secure together the parts 5, 2, 12, and 1^a.

The numeral 15 indicates side bearings applied on the end portions of the compression member 1, which form no part of our invention 30 and may be of any suitable construction.

What we claim, and desire to secure by Letters Patent of the United States, is as follows:

1. In a truck-bolster, the combination 35 with tension and compression members, of lock-blocks seated in the ends of said compression member and removable therefrom only by outward movement, the ends of said tension member being arranged to prevent 40 outward movement of said lock-blocks, when the parts are assembled, substantially as described.

2. In a truck-bolster, the combination 45 with tension and compression members, of wedge-shaped lock-blocks seated in the ends of said compression member and serving to clamp the ends of said tension member to the ends of said compression member, substantially as described.

3. In a truck-bolster, the combination 50 with compression and tension members, of lock-blocks seated in the ends of said compression member and removable therefrom only by outward movement, the ends of said tension member being bent over the outer 55 ends of the said blocks and preventing removal of the blocks, when the parts are assembled, substantially as described.

4. In a truck-bolster, the combination 60 with tension and compression members, of wedge-shaped lock-blocks seated in the ends of said compression member and coöperating with inclined bearing-surfaces in the ends of said compression member, to clamp the ends of said tension member, the ends of said 65 tension member being bent down over the outer ends of said lock-blocks and being secured thereto, substantially as described.

5. In a truck-bolster, the combination 70 with a channel-shaped compression member and a flat tension member, of lock-blocks seated in the outer ends of said compression member and removable therefrom only by outward movements, the ends of said tension member being clamped against the ends of 75 said compression member, by said lock-blocks and being turned downward and riveted to the outer ends of said lock-blocks, substantially as described.

6. In a truck-bolster, the combination 80 with a compression member having flanged ends, of lock-blocks seated in the flanged ends of said compression member and having projecting side lugs that overlap and embrace the end flanges of said compression 85 member, and a tension member passed between said lock-blocks and the ends of said compression member and turned downward and secured to the outer portions of said lock-blocks, substantially as described. 90

In testimony whereof we affix our signatures in presence of two witnesses.

LEE W. BARBER.
EDWIN W. WEBB.
